United States Patent Office

Des. 208,912
Patented Oct. 17, 1967

208,912

MODEL FOR ATOMIC DISPLAY

Fred M. Siptrott, 3011 Hardies Lane,
Santa Rosa, Calif. 95401

Filed Aug. 22, 1966, Ser. No. 3,545

Term of patent 14 years

(Cl. D25—1)

Fig. 1.

Fig. 2.

Fig. 3.

FIGURE 1 is a front elevational view of a model for atomic display, showing my new design,

FIGURE 2 is a plan view of FIGURE 1,

FIGURE 3 is an elevational view taken from one side of FIGURE 1, and

FIGURE 4 is a perspective view thereof.

I claim:

The ornamental design for a model for atomic display, as shown.
